ATTORNEY

UNITED STATES PATENT OFFICE.

WILLIAM W. HAYDEN, OF NEWARK, NEW JERSEY.

DESIGN FOR A HANDLE FOR CUTLERY, &c.

SPECIFICATION forming part of Design No. 21,812, dated August 30, 1892.

Application filed July 20, 1892. Serial No. 440,680. Term of patent 3½ years.

To all whom it may concern:

Be it known that I, WILLIAM W. HAYDEN, a citizen of the United States, and a resident of Newark, in the county of Essex and State of New Jersey, have invented and produced a certain new and useful Design for a Handle for Cutlery, of which the following is a specification.

Reference is to be had to the accompanying drawings forming a part of this specification, in which the figure clearly illustrates my newly-designed handle for cutlery and other articles.

The handle displays the outward curves *a a* and *b b* and the inward curves *c c* and *d d*. At the end of the handle appears the scrolls

e e and the series of interposed ribs or corrugations *f*. One side or edge of the handle shows a vine-like ornament *g*, which appears as if wrapped around the edge, while at the opposite edge appears a similar ornament *h*, which terminates in a scroll *h'* at the end of the handle and at the point of the handle joins a leaf-ornament *h²*.

I claim—

The design for a handle for cutlery, substantially as shown and described.

WILLIAM W. HAYDEN.
